UNITED STATES PATENT OFFICE.

FRED I. GETTY, OF JENNINGS, LOUISIANA.

WHIPSTOCK FOR WELLS.

Application filed October 1, 1923. Serial No. 685,827.

To all whom it may concern:

Be it known that I, FRED I. GETTY, a citizen of the United States, residing at Jennings, in the parish of Jefferson Davis and 5 State of Louisiana, have invented certain new and useful Improvements in Whipstocks for Wells, of which the following is a specification.

The invention relates to whipstocks, and 10 has as an object the provision of a device of this character which may be set in a well and locked therein against movement during subsequent operation. A further object of the invention is the provision of 15 a tool for setting whipstocks having provision for removing from the well the head of a stud bolt which is sheared off after the whipstock is set. A further object of the invention is the provision of a whipstock 20 that will be pressed firmly against the side of the casing at its upper end.

Other objects of the invention will appear from the following description when read in connection with the accompanying drawings 25 showing an illustrative embodiment of the invention, and in which—

Fig. 1 is an elevation of the apparatus before the whipstock is finally placed in its permanent position.

30 Fig. 2 is a like view of the whipstock fixed in position, showing a wedge with smooth edges.

Fig. 3 is a detail view similar to Fig. 1 upon an enlarged scale, showing the lower 35 end of the whipstock before it is placed in its permanent position.

Fig. 4 is a detail view similar to Fig. 2, upon an enlarged scale, showing the lower end of the whipstock placed and locked in 40 position.

Fig. 5 is a detail view partly in central vertical section, upon an enlarged scale, of the upper end of the whipstock and the setting tool.

45 Fig. 6 is a plan view of the whipstock.

Fig. 7 is a detail section on line 8, 8 of Fig. 5 of the end of the setting tool only.

Fig. 8 is a side elevation of the form of 50 a stud bolt adapted to support the whipstock and coat with the setting tool.

Fig. 9 is a bottom plan view of the whipstock.

Fig. 10 is a detail elevation similar to Fig. 3 and showing a modified form of 55 wedge and operating mechanism.

Fig. 11 is an elevation upon an enlarged

scale of a still further modified form of wedge.

In the drilling of oil wells, it is sometimes necessary to offset the hole at the bottom. This may be due to loss of tools, pipe or other things in the well, or it may be desirable after the well has become old and nonproductive, due to various causes, such as the destruction of the screen or the clogging of the liner with paraffine. It is the practice to insert a tool known as a "whipstock," which is in effect a wedge and which is adapted to cause a cutting tool lowered into the well to operate against the casing at one side and make an opening therein, and also to guide drilling tools through said opening when the same are subsequently lowered into the well to operate upon the material outside of the casing. A difficulty with whipstocks heretofore in use is that there has been no provision for locking the same tightly in place, with the result that the revolution of the cutting tool in contact therewith at times has moved the whipstock about within the casing and interfered with the action of the cutting tool upon a single point of the casing.

To overcome this difficulty, the present invention provides a whipstock 10, which is tapering upon one side 11 to a point 12 where the whipstock bears against the casing 13 of the well, and has a taper 14 from the point 12 to the lower end thereof. To cause the upper end 15 to bear tightly against the side of the casing 13 and to lock the whipstock firmly within the well a wedge 16 is provided which presses the point 12 tightly against the casing, thereby acting as a fulcrum to force the end 15 against the opposite side of the casing.

The wedge 16 is adapted to slide between a pair of flanges 17, 18, as most clearly shown in Fig. 9, and is retained therein by means of a bolt 19, the end of which bolt 100 coats with the slot 20 in the wedge. The side of the wedge 16 acts against the whipstock 14 by bearing against the bottom end thereof between the flanges 17-18.

To hold the wedge 16 in its inactive position while the tool is being lowered into the well, a pin of some easily sheared material, as for instance brass, is passed through the flanges 17-18, and through a hole 22 in the end of the wedge. To set the wedge 16 when 110 the tool has been lowered to the desired position there is shown a piece of pipe 23, having

its end closed and suspended from a bolt 24 passing through an opening in the closed end of the pipe, and screwed into a tapped opening in the bottom end of the whipstock, 5 as most clearly shown in Fig. 3. While the device is being lowered into the well the parts already described occupy the position shown in Figs. 1 and 3, and when the pipe 23 comes in contact with the liner 25 in the 10 lower portion of the well, the bottom end of the wedge seats on the pipe 23, and the weight of the device as it descends further will shear the pin 21, and the continued movement downward of the whipstock will 15 cause the wedge 16 to impinge upon the pipe 23, thereby driving home the wedge into the position shown in Figs. 2 and 4.

It may be desirable to offset the well at some point more or less distant from the 20 upper end of the liner or the lost tools in the well, against which the bottom end of the pipe 23 impinges for driving of the wedge 16. For this purpose a pipe or a string of pipe of the desired length may be 25 screwed into the coupling 26 upon the lower end of the pipe 23. To lower the whipstock into position a tool 27 is provided, the details of which are more clearly shown in Figs. 5 and 8. This tool supports the 30 whipstock by means of the bolt 33, the tool being attached to a string of pipe 29, by means of which it is let down into place in the well. The lower flattened end of the tool 27 is shown as provided with a slot 30 35 and with pockets 31, 32 opposite each end of the slot.

To coact with the tool 27 there is shown a stud bolt 33 screwed into a tapped opening in the whipstock and projecting through 40 the slot 30, the space 34 between the pockets 31, 32 giving access to the head of the bolt for the purpose of placing the same in position, and attaching the tool 27 to the whipstock.

45 When the whipstock has been lowered to place the weight of the whipstock with the weight of the tool 27 and the drill stem or pipe attached to the same will readily shear the pin 21 and drive the wedge 16 prior to shearing of the bolt 33. If the mere weight of the parts 27 and 29 is not sufficient to then shear the bolt 33 the same may be lifted and dropped through a slight distance to bring about the desired shearing of this 50 bolt when the head thereof will fall to the lower pocket 31 and be removed from the well with the tool 27. The upper edge of the lower pocket 31 is shown as beveled at 55 to more surely guide the head of the bolt into the lower pocket. Preferably, the bolt is weakened by means of a circumferential channel 36, as shown in Fig. 9. The concavity of the whipstock throughout its wedging surface is best shown in Fig. 5.

60 A modified form of the device is shown in

Fig. 10, which will permit the whipstock to be set at any desired point above the liner, without any intervening pipe to support it. A coil spring 38 is mounted in a recess 39 in the back of the whipstock adjacent its 70 bottom end, one end of the spring being anchored to a pin 40 and the other end being secured at 41 to the end of the wedge, the pin 21 being provided as in the form of the invention first described. This form of the invention has the wedge 16' preferably toothed, as shown at 42. When the end of the wedge 16' impinges against the liner 25 the pin 21 is sheared and contraction of the spring 38 draws the wedge upward and 80 holds it by yielding pressure. The whipstock may then be drawn upward in the well casing to any desired point, after which a slight downward movement will cause the teeth of the wedge to sink into the adjacent surface of the well casing and effectually wedge and anchor the whipstock in place.

85 A modification of the wedge is illustrated in Fig. 11. This is intended to be used with the setting pipe 23 of Figs. 1 to 4 inclusive, which form of wedge is toothed on both sides, the teeth 43 acting to prevent the lifting of the whipstock by biting into the metal thereof and the teeth 44 acting to prevent the lifting of the wedge by biting into the casing, thereby serving to make the whipstock immovable when once placed.

90 Minor changes may be made in the physical embodiment of the invention without departing from its spirit.

100 I claim:

1. A whipstock comprising an elongated body having a taper extending throughout a major portion thereof providing a wedging face, a portion tapered oppositely from the angle of said wedge extending from a point adjacent to the lower end of said wedge to the lower end of the body, means to press the portion of the body between said tapered portions against the interior of a well casing, whereby to cause the upper end of the body to hug the opposite surface of the well casing.

110 2. A whipstock comprising an elongated body having a taper extending throughout a major portion of the length of the body providing a wedging face, a portion tapered oppositely from said wedging face to the lower end of the body, locking means to press the portion of the body between said tapered portions against the interior of a well casing whereby to cause the upper end of the body to hug the opposite interior portion of the well casing and to lock the body against movement within the casing.

120 3. A whipstock for wells comprising an elongated body having a tapered portion providing a wedging face, wedging means carried by the lower portion of the body, means to bring said wedging means into

action at will to lock the body against movement within the well casing.

4. A whipstock for wells comprising an elongated body having a tapered portion 5 providing a wedging face, locking means carried by the lower portion of the body, means to bring said locking means into action at will to lock the body against movement within the well casing, and means to 10 prevent premature action of said locking means.

5. A whipstock for wells comprising an elongated body having a taper extending throughout a major portion thereof to provide a wedging face, locking means carried by said body, means carried by said body adapted to contact with an object in the well to bring said locking means into action to lock said body against movement within 20 a well casing.

6. A whipstock for wells comprising, in combination, an elongated body having a taper extending throughout a major portion of its length, providing a wedging face, an 25 oppositely directed taper extending through a minor portion of its length to the bottom of the body, a wedge movably carried by said body adapted to coact with the side of the lower end thereof opposite said last 30 named taper to press the portion of the body between said tapered portions against a wall of the well casing, whereby to cause the upper end of the body to hug the opposite side of the interior of the casing and 35 to lock the body against movement, and means carried by the body adapted upon

contact with an object in the well to drive said wedge.

7. A whipstock for wells comprising, in combination, an elongated body having a 40 tapered portion extending throughout a major portion of the length thereof, a wedge carried by the lower portion of said body, means to prevent premature action of said wedge, and means to drive said wedge to 45 lock said body within a well casing at a predetermined location therein.

8. A whipstock for wells comprising, in combination, an elongated body having a 50 tapered portion extending throughout a major portion of the length thereof, a wedge carried by the lower portion of said body, teeth upon a side thereof to render said wedge immovable when driven, means to prevent premature action of said wedge, and 55 means to drive said wedge to lock said body within a well casing at a predetermined location therein.

9. A whipstock for wells comprising an elongated body having a taper extending 60 throughout a major portion thereof providing a wedging face, a stud bolt engaging a tapped opening in said face, means coacting with said bolt for lowering the body into the well, comprising a head having a slot 65 adapted to coact with the shank of the bolt, a pocket adapted to receive the head of the bolt when sheared by weight of the tool after the body has been placed, and an opening 70 opposite the slot to give access to the head of the bolt for assembly.

FRED I. GETTY.
